CLAIM

The ornamental design for a baking tin, as shown and described.

DESCRIPTION

FIG. 1 is a top plan view of a baking tin embodying my new design;

FIG. 2 is a bottom plan view thereof;

FIG. 3 is a side elevation view thereof, the other side elevation view being a mirror image thereof;

FIG. 4 is a front elevation view, the rear elevation view being a mirror elevation thereof;

FIG. 5 is a top plan view of a second embodiment of the baking tin of FIGS. 1-4;

FIG. 6 is a bottom plan view thereof; and,

FIG. 7 is a side elevation view thereof, all other side views being identical.
